ATTY.

UNITED STATES PATENT OFFICE.

LEWIS LEWISON, OF HAMILTON, ONTARIO, CANADA.

PASTRY-MAKING DEVICE.

1,293,819.

Specification of Letters Patent. Patented Feb. 11, 1919.

Application filed February 19, 1917. Serial No. 149,529.

To all whom it may concern:

Be it known that I, LEWIS LEWISON, a subject of the King of Great Britain, residing at Hamilton, in the county of Wentworth and Province of Ontario, Canada, have invented certain new and useful Improvements in Pastry-Making Devices, of which the following is a specification.

My invention relates to a machine for molding and baking what are termed and commonly known as ice-cream cones, and consists essentially of a number of series of centrally divided female dies, the respective halves of each said series being hingedly secured each to the other at their lower end parts, an integral fulcrumed arm extending therefrom in one direction, and a handle extending therefrom in the opposite direction, corresponding male dies together with a carrier therefor, an integral arm on the carrier pivotally connected to the arm on the female dies, and an integral handle extending from said carrier in the opposite direction, and parallel to the handle on the female dies, and a novel lock adapted to lock said handles together.

My invention has for its objects, first, to provide means in a machine of the class specified, whereby pastry cones may be molded and baked having embossed ornamental designs or lettering on their exteriors, and be easily and readily withdrawn from the die after baking, without destroying or marring said lettering in so doing, 35 second, to provide a machine of this class to mold and bake a number of such cones at one operation, third, to afford facilities for the opening of the female dies to provide for the withdrawal of the finished cone.

40 A further object is to provide such a machine being inexpensive to manufacture, having simplicity in its structure, and easy and simple to operate. Another object is to afford facilities for the provision of more dies, without departing from the original method of manipulation thereof.

50 A still further object is to provide an improved latch or lock to secure the two handles each to the other while the cones are in process of baking.

These objects, together with other objects apparent to those skilled in the art may be attained by the construction, combination and arrangement of parts as will be hereinafter fully described, illustrated in the

accompanying drawings, and pointed out in the claims hereunto annexed.

Reference being had to the drawing, Figure 1 is a top view of the entire machine showing it as when the cones are in process 60 of baking, Fig. 2 is a part sectional side elevation of the same as seen on the line X—X in Fig. 1, Fig. 3 is a side elevation of the machine in open position, the pastry cones having been just removed, and the 65 female die portion shown in section, Fig. 4 is a detailed view of the female dies in process of opening, and, Fig. 5 shows a modified form of the pivotal joints of the 70 arms.

Similar reference characters refer to similar parts throughout the several views.

Referring again to the drawing, A indicates a coverless and bottomless oven wherein is provided a gas burner 2 suitably connected to the gas supply by a pipe 3. The said oven is secured at its front and rear parts to substantial standards or uprights 4, which are provided with bottom lips 5 through which screws 6 pass and secure 80 them to the floor, table or bench, as the case may be.

The tops of the standards 4 are adapted to support the longitudinal arms 7 and 8 of the conical female dies B. The said dies 85 are arranged in two transverse sections or series B¹ and B², and the dies in each series are in alignment one with the other. Each series is centrally divided and consists of a central integral member 9, comprising one 90 equal half part of the two said series. The other half parts 10 and 12 of said series are hinged at their lower end parts to the lower end parts of the member 9 at 13 and 14, respectively.

95 The arm 7 is provided with a narrow end part 15 which is slightly hollowed on its under side to rest upon a fulcrum 16, and a longitudinal handle 17 is centrally secured to and extends from the end of the arm 8. The arm 7 may be provided with an integral leg 7¹ adapted to rest upon the floor, thereby eliminating the necessity of the provision of the fulcrum 16, if desired, as illustrated in Fig. 5 of the drawing.

100 19 are conical male dies conforming to and in relative position to the respective female dies B, and are rigidly secured to a carrier 20 by means of screws 21, or they may form an integral part of the carrier 21.

if desired in practice. The exterior of said male dies are slightly smaller than the interior of the female dies, leaving a narrow intervening space between the same when closed. 19¹ are annular rings on the male dies adapted to enter a corresponding annular groove in the female dies, with an intervening space between forming a narrow flange on the pastry cones. 20¹ is a pointed rib on the carrier 20 adapted to engage a corresponding pointed groove 9¹ in the central member 9, and to sever the possible layer of paste connecting one series of dies with the other.

15 Pins 34 are provided rigid with the arms 7 and 8, respectively, which pins are adapted to enter corresponding recesses in the arms 22 and 24, respectively, in order to govern and direct the accurate entrance of 20 the male dies 19 into the female dies B.

The carrier 20 is provided with an integral arm 22 which is pivotally connected to the arm 7 at 23, and another arm 24 extends parallel with the arm 8 from the opposite 25 or front end of said carrier, and is provided with an elongated handle 25 similar to and parallel with the handle 17. In the modified form, shown in Fig. 5 of the drawing, I provide an integral counter weight 30 22¹ on the arm 22.

When the dough or batter is placed in the female dies B, and the male dies 19 are placed in position for baking as shown in Figs. 1 and 2, the handles 17 and 25 are 35 locked together in order to retain the carrier 20 securely in position, and by the novel means to be described.

The handles 17 and 25 are long enough 40 to be somewhat resilient, and may be pressed together at their ends by exerting a sufficient amount of strength. A block 26 is loosely connected by means of suitable links 27 to the end of the handle 17, and the side 28 of said block farthest from the links 45 27 is hollowed to conform substantially to the contour of the handle 25. When the machine is open, the said block is hanging as shown in Fig. 3, but when it is required to lock the handles, the block is placed with 50 its side 29 on the top of the handle 25, then by upward pressure effected upon the integral handle 30 the block is brought to the position shown in Fig. 2, securely locking said handles. By effecting a slight downward jar to the handle 30, the block is again dislodged. To facilitate the easy adjustment of said block, and to prevent the same from sliding too far upon said handle, I employ a lug 30¹ integral with the handle 30. 60 The said lug tends to augment the leverage when applying the block 26 to the handle 25, and engages the end of said handle when the block is locked in position thereon, as shown in Fig. 2.

65 The gas jets 31 of the burner 2 are so posi-

tioned thereon as to deliver the flame between and at the sides of the dies as shown in Fig. 1, in order to distribute the heat more equally to the pastry. The machine may be readily rotated transversely of the 70 oven in depressions in the top of the standards 4 to give equal heat to all parts of the pastry cones.

When the pastry is sufficiently baked, the carrier 20 is lifted as shown in Fig. 3, and 75 the handle 25 may be hooked to a suitable hook 32 in order to retain it in that position. The female dies B are then opened, as illustrated in the same figure, by means of downward pressure effected upon the 80 handle 17. When this pressure is brought to bear on said handle, the half part 12 of the series B² of female dies is first opened, as illustrated in Fig. 4 of the drawing. The said part 12 is connected by a slide 85 catch 35 to the central member 9. Thus it will be seen that when the part 12 is entirely opened, the catch 35 is drawn to its extremity, and the continuance of pressure on said handle will consequently open the series 90 B¹ of dies. This operation provides for the ready extraction of the cones from the female dies without breaking or defacing the raised lettering or ornamental design thereon formed by the corresponding molds 33 in 95 said dies. When the cones are removed, the female dies are permitted to resume their previous position simply by means of their own weight.

It will be perceived that by the addition of 100 several series of female dies B, and likewise corresponding male dies 19, the operation of the machine will be unaltered.

Having now fully described my invention, what I claim and desire to secure by Let- 105 ters Patent of the United States, is:—

1. In a machine of the class described, a coverless oven and heater therefor, a central member comprising one half part of each of two separate series of female dies, side members comprising the other halves of said series and hinged at their lower end parts to the lower end parts of the central member, an integral arm on each said side member adapted to support the female die members 110 over the oven and heater, a carrier pivoted to one of said arms, a fulcrum adapted to support the end of the same arm, a handle secured to the end of the other arm, male dies secured to the carrier adapted to fit the 115 female dies with an intervening space between, a handle secured to the carrier, and means for locking the two said handles together at their ends, for the purpose set forth.

2. In a machine of the class described, an oven and heater therefor, a number of series of centrally divided female dies, the respective halves of each series being hingedly secured together at their lower end parts, a 120

rear arm integral with and extending from one outer half part, a fulcrum adapted to support the arm, a forward arm integral with and extending from the other outer half part, said arms together adapted to support the series of female dies over the oven and heater, a handle fixed to the forward arm adapted when downward pressure is applied to it to open the first series of female dies, means to open the remaining series when the pressure is continued, a carrier member pivoted to the rear arm, male dies secured to the carrier member and adapted to enter the female dies with an intervening space between, a handle fixed to said carrier member extending parallel to the handle on the forward arm when the machine is closed, means for locking said handles together, and means for directing the true entrance of the male dies into the female dies.

5 10 15 20

3. In a machine of the class described, an oven and heater therefor, a central member comprising one half part of each of two separate series of female dies, side members 25 comprising the other half parts of said series hinged at their lower end parts to the lower end parts of the central member, an integral arm on each side member adapted to support the female die members over the oven and heater, a carrier pivoted to one of said arms, a leg integral with the same arm at the end thereof, a counter weight for and integral with the carrier, a handle secured to the other arm, male dies secured to the carrier adapted to fit the female dies with an intervening space between, a handle secured to the carrier, and means for locking the two said handles together at their end parts, for the purpose set forth.

30 35 40

In testimony whereof I affix my signature in the presence of two witnesses.

LEWIS LEWISON.
